UNITED STATES PATENT OFFICE.

J. W. FAWKES, OF CHRISTIANA, PENNSYLVANIA.

IMPROVEMENT IN STEAM-PLOWS.

Specification forming part of Letters Patent No. 26,422, dated December 13, 1859.

To all whom it may concern:

Be it known that I, J. W. FAWKES, of Christiana, in the county of Lancaster and State of Pennsylvania, have invented certain new and useful Improvements in Locomotive or Steam Plows; and I do hereby declare that the following is a full, clear, and exact description of the same, reference being had to the annexed drawings, making a part of this specification, in which—

Figure 1 is a side elevation of a locomotive or steam plow with my improvements applied to it. Fig. 2 is a plan or top view of the same. Fig. 3 is a detached view of a clutch arrangement pertaining to the same. Fig. 4 is a detached view of an automatic pawl arrangement pertaining to the same.

Similar letters of reference indicate corresponding parts in the several figures.

The invention consists, first, in the arrangement of a peculiar mechanism employed for elevating the plow-frame, whereby the latter may be actuated so as to incline the plows, and the mechanism stopped automatically when the frame and plows are sufficiently elevated.

The invention consists, second, in a novel combination, with the first feature, of a holding-pawl and brake, substantially as hereinafter shown and described, to facilitate the adjustment of the plows to their work.

To enable those skilled in the art to fully understand and construct my invention, I will proceed to describe it.

A represents a traction-engine the front part of the framing of which is supported by two wheels, B B, the axle C of which may be turned by a segment, a, and screw b in order to guide the machine. The back and principal part of the framing is supported by a drum, D, of slightly bilge form, said drum serving as the driver or propeller, and which has motion communicated to it from the steam-cylinders in any proper way.

The above parts do not require a minute description, as they have been formerly used and may be seen in a patent granted to me January 26, 1858.

At the back part of the engine there is a shaft, E, which is allowed to turn freely in its bearings. This shaft E has a ratchet, c, at one end, into which a pawl, d, catches, and two pulleys, e e, are placed on this shaft,

one near each end, around which chains or ropes F F pass, said chains or ropes having each an auxiliary chain or rope, f, attached. These chains or ropes pass over pulleys g, attached to bars G G, which project from the back part of the engine. The ends of the chains or ropes F F f f are attached to the angles of a rhomboid frame, H, which has an oblique position relatively with the engine and is directly behind it, as shown in Figs. 1 and 2.

The frame H is the plow-frame, and the plows are attached to it as follows: The plows I may be of the usual or any proper form, and they are attached to frames J in pairs. The frames J are simply iron bars bent so as to form two parallel sides, at a suitable distance apart, to each side of which a plow, I, is permanently attached, one plow being slightly in advance of the other and turning a furrow-slice which will be lapped by the one turned by the hindmost plow. Each frame J has a gage-wheel, K, attached to its front end, and these wheels determine the depth of the furrows.

The frames J are attached to the frame H as follows: To the front end of each frame J the lower end of a bar, L, is pivoted. These bars pass upward through slotted plates h, attached to the front part of the frame H, and through the upper part of each bar L, above its plate h, a wooden pin, i, passes. The back part of each frame J has a curved bar, j, attached, and these bars are fitted in slotted plates k, attached to the back part of the frame H, both to its upper and lower side, the slots of the plates k extending to the back ends of the plates, as shown clearly in Fig. 2. The plates k are secured to the frame H by screw-bolts l, which pass through oblong slots in the back bar of the frame, and admit of the smaller frames J being adjusted parallel with each other and severally in line with the planes of their movement. Each frame J is connected by a chain, K', with a bar, L', attached to the engine. The chains K' are attached to the bar L' by means of wooden pins m, which pass through loops n on the bar L', and through the chains K. (See Fig. 1.) Through each bar j L pins a* pass, which determine the length of the play or movement of said bars.

The shaft E has also a pulley, o, placed on it, around which pulley a belt, p, passes, said belt also passing around a pulley, q, on a clutch,

r, which is placed loosely on a small shaft, *s*, in the framing of the engine. The shaft *s* is connected by means of suitable gearing with the driving mechanism of the drum, and consequently the former rotates with the latter, and a gear-wheel, *t*, on the shaft *s* has an aperture made in it to receive a pin, *u*, at the side of the pulley *q* when the latter is moved in contact with said wheel. (See Fig. 3.) The pulley and clutch *q r* are operated by a lever, *M*, which has an oblique slot, *v*, at its outer end, through which a lever, *N*, has a rod, *O*, attached to it, and this rod is connected by a chain or cord, *a'*, with a forked lever, *b'*, which is attached to one of the bars *G*. One of the chains or ropes *F* is fitted in the forked end of the lever *b'*, and said chain or rope has a button or projection, *c'*, thereon, the use of which will be presently shown.

P is a rod one end of which is attached to a lever, *Q*, on the framing of the engine, the other end being attached to a brake, *R*, also attached to the framing of the engine, and near a wheel, *S*, and one end of the shaft *E*. The brake *R* is simply a lever having its lower part flattened and curved to correspond with the periphery of the wheel *S*. The fulcrum *d'* of the brake *R* has a projection, *e'*, on it, and this projection is directly under and acts against the pawl *d*, elevating it free from the ratchet *c*, when the lever *Q* is drawn back and the brake *R* thrown in contact with the wheel *S*.

The operation of the machine is as follows: As the machine is propelled along, the plows *I* turn the furrow-slices in the ordinary way, any proper number of plows being used, according to the size and power of the machine. Each frame *J* is allowed an independent movement in the common frame *H*, as the bars *L, l* have a certain degree of vertical play in their respective plates *h, h*. Each frame *J* may therefore fall in passing over a depressed surface of the earth without affecting the frames at its side, and each frame may rise and carry with it the common frame *H* for a certain distance without affecting the other frames. It will be seen, therefore, that each pair of plows—that is to say, the two plows of each frame *J*—are allowed an independent, adjustable movement to conform to the inequalities of the surface of the earth over which they pass.

In case of either of the plows of a frame meeting with an obstruction, the wooden pin *m*, which connects its chain *K'* with the bar *L'*, will break, and the bar *L* of the obstructed frame *J* will be forced forward by the movement of the frame *H*, and the wooden pin *i* will also be broken and the frame *J* consequently detached from the common frame *H* without affecting either of the other frames *J*. By this means none of the parts of the machine will be strained or injured in consequence of either of the plows being obstructed by obstacles in its path.

When the whole gang of plows are to be raised out of and free from the earth the attendant moves forward the upper part of the lever *N*, and the lever *M* is thereby actuated and the clutch *r* attached to wheel *t*. Motion is consequently given the shaft *E* by the belt *p*, and as the shaft *E* rotates the chains *F F* will be wound on the pulleys *e e*, and the front part of the plow-frame *H* will be first elevated, as the supplemental or auxiliary chains or ropes *f* are rather shorter than the end portions of *F*. This elevation of the front end of the frame *H* inclines upward the front ends of the plows *I* and causes the same to pass upward out of the ground, and when the inclination has been given said frame *H* the end plates of the chains *F* then act on the frame, which is raised bodily until the plows are free from the earth. When the plows have arrived at a suitable height the button or projection *c'* will actuate the lever *b'*, and the rod *O* will throw the lever *N* back to its original position, and the pulley *q* will be disengaged from wheel *t* and the shaft *E* stopped. By this automatic stop mechanism the machine is prevented from having its parts deranged by any undue upward movement of the plows. The plows are retained in proper position by the pawl *d*, which, by engaging with the ratchet *c*, prevents the shaft *E* from turning under the weight of the plows and their frames.

In order to adjust the plows to their work, the attendant throws forward the upper end of lever *Q*, and by that means applies the brake *R* to the wheel *S*. Simultaneously with this movement of the brake the pawl *d* is raised free from the ratchet *c* by the projection *e'* on the fulcrum-shaft *d'* of the brake *R*. By this means the frame *H* with the frames *J* and the plows are allowed to descend gradually.

I do not claim the driving-drum *D*, nor the mode of turning the front wheels, *B*, of the carriage of the traction-engine; nor do I claim broadly the employment or use of a series of plows placed behind a traction-engine irrespective of the mode of connection to the engine and the arrangement herein described; but,

Having thus described my invention, what I claim as new, and desire to secure by Letters Patent, is—

1. The arrangement of the clutch *r*, levers *M N*, rod *O*, lever *b'*, and button or projection *c'* on the chain *F*, whereby the chains *F F* are wound on the pulleys *e e* of the shaft *E* and stopped automatically at the proper time, for the purpose set forth.

2. In combination with the above, the brake *R* and pawl *d*, when applied to the machine to operate simultaneously, as and for the purpose described.

J. W. FAWKES.
